J. J. HENNESSY.
LOCOMOTIVE JOURNAL LUBRICATOR
APPLICATION FILED APR. 23, 1921.

1,416,710.

Patented May 23, 1922.

Inventor,
J. J. Hennessy:—
By F. R. Cornwall, ^{Attest.}

UNITED STATES PATENT OFFICE.

JAMES J. HENNESSY, OF NEW YORK, N. Y.

LOCOMOTIVE JOURNAL LUBRICATOR.

1,416,710.

Specification of Letters Patent. Patented May 23, 1922.

Application filed April 23, 1921. Serial No. 463,842.

To all whom it may concern:

Be it known that I, JAMES J. HENNESSY, a citizen of the United States, residing at the city of New York, county of New York, 5 and State of New York, have invented a certain new and useful Improvement in Locomotive Journal Lubricators, of which the following is a full, clear, and exact description, such as will enable others skilled 10 in the art to which it appertains to make and use the same, reference being had to the accompanying drawings, forming part of this application.

My invention relates to improvements in 15 locomotive journal lubricating devices, particularly of the type disclosed in my co-pending patent applications, Serial Numbers 397,341 and 397,342, filed July 19, 1920, and Serial Number 352,098, filed January 20 17, 1920.

The principal objects of my present invention are, to generally improve upon and simplify the construction of the lubricating devices set forth in my aforesaid applications; to provide a construction wherein the container or cellar of the device is formed in a single piece, preferably by casting, thereby greatly decreasing the cost of manufacture of the complete device; 30 further to provide a journal lubricating device that has relatively few parts, thereby reducing to a minimum the liability of the device getting out of order while in service; and, further, to provide a lubricating device that is wholly automatic in action and very effective in performing its intended 35 functions.

With the foregoing and other objects in view, my invention consists in certain novel 40 features of construction and arrangement of parts, hereinafter more fully described and claimed, and illustrated in the accompanying drawings, in which—

Figure 1 is a vertical section taken 45 lengthwise through the approximate center of a journal lubricating device of my improved construction.

Figure 2 is a cross section taken on the line 2—2 of Figure 1.

50 Figure 3 is a cross section taken on the line 3—3 of Figure 1.

Referring by numerals to the accompanying drawings, which illustrate a prac-

tical embodiment of my invention, 10, 10 designate the side walls, 11, 11 the end 55 walls, and 12 the bottom of a substantially rectangular container or cellar that is preferably of integral structure.

In order that this cellar may be properly applied to the journal of a wheel carrying 60 axle, the upper portions of the end walls 11 are cut away on radii that are slightly greater than the radius of the journal. Formed within the cellar immediately adjacent to the end walls 11 are vertically 65 disposed pockets 13 that receive combined packing members and dust guards 14 of wood or fiber and which have their upper edges formed so as to fit snugly against the periphery of the axle at the ends of the 70 bearing portion thereof. These packing members prevent the leakage or discharge of oil and waste from the ends of the cellar and also prevent dust, sand and like foreign matter from entering the cellar 75 through the joints between its ends and the journal.

Formed on the inner faces of the side walls 10, 10 of the cellar and in a plane a substantial distance above the bottom 12 80 are horizontally disposed shoulders 15 that extend between the pockets 13, and resting upon these shoulders are the side edges of a relatively shallow pan 16. This pan is preferably formed of sheet metal and it 85 is adapted to contain waste or like absorbent material and retain the same in contact with the underside of the journal with which the device is associated.

Formed in the bottom of the pan and 90 preferably at or near the center thereof is an aperture 17 and projecting upwardly from said bottom and disposed about said aperture is an annular wall 18, the height 95 of which is practically the same as that of the walls of the pan. Formed integral with the bottom 12 of the cellar and extending inwardly from one end thereof is a block 19, the inner end thereof terminating in a vertically disposed tubular member 20 that 100 is centrally arranged within said cellar. The upper portion of tubular member 20 projects upwardly through the opening 17 in pan 16 and terminates in a horizontal plane slightly above the plane occupied by 105 the top of wall 18. That portion of bot-

tom 12 that is below and adjacent to the lower end of tubular member 20 is depressed to form a sump 21. The bottom of this sump is provided with an opening that is normally closed by a plug 22 and which latter, when removed, permits the liquid lubricant to be entirely drained from the cellar.

Removably positioned in the lower end 10 of the tubular member 20 is a ring 23, the upper surface thereof forming a seat for a disc valve 24 and depending from the latter is a loop 25 through which passes a transversely disposed pin 26, the ends 15 thereof being seated in ring 23. Formed within tubular member 20 a short distance above ring 23 and valve 24 is an annular flange 27, the upper surface thereof forming a seat for a spherical valve 28. Bearing 20 on top of this valve 28 and yieldingly holding the same upon its seat is the lower end of a relatively light compression spring 29, the upper end of which bears against a pin or pins 30 that are seated in 25 tubular member 20.

Formed through the lower portion of block 19 is a longitudinally disposed bore 31, the outer end of which is closed by a plug 32 and the inner end communicating 30 with that portion of the chamber in member 20 between valves 24 and 28. Arranged for reciprocating movement within bore 31 is a piston 33 that is connected by a strap 34 to a plunger 35 and the latter being arranged 35 for reciprocating movement in a bore 36 that is formed in block 19 above and to one side of bore 31. The inner portion of plunger 35 is reduced in diameter and arranged thereupon and bearing against 40 a shoulder at the inner end of said reduced portion is a compression spring 36^a that yieldingly resists inward movement of said plunger. The outer end of plunger 35 is adapted to engage the inner face of the 45 hub A of the adjacent wheel and which latter, it will be understood, is carried by the axle B having the journal to which the lubricator is applied.

My improved lubricating device thus constructed is applied to the journal of an axle 50 and maintained in position in any suitable manner. Before installation, the pan 16 is packed with waste or like fibrous material and a supply of liquid lubricant is delivered 55 into the cellar through a suitable filling spout S that is located at the inner end of said cellar.

It will be understood that all car axles, in addition to their rotary movement, have a 60 certain amount of longitudinal movement, that is, a movement transversely of the car or locomotive body and in my improved device this movement is utilized for pumping the liquid lubricant from the bottom of 65 the cellar and the sump therein, upwardly

into the body of fibrous material that is supported by pan 16 and makes direct contact with the journal.

As axle B moves lengthwise in one direction, it forces plunger 35 inwardly against 70 the resistance offered by spring 36^a and such inward movement is transmitted to piston 33. As the latter moves toward tubular member 20, a portion of the liquid lubricant in chamber 31 in front of said piston and 75 in the chamber between valves 24 and 28 will be forced upwardly through tubular member 20 past valve 28 and a corresponding amount of liquid lubricant will be discharged from the upper end of said tubular 80 member directly into the center of the body of waste to be distributed thereby directly on the surface of the journal. As the axle moves in a reverse direction, plunger 35 and piston 33 will move outwardly under 85 the influence of spring 36^a and as a result of the suction produced in the inner end of chamber 31, valve 24 will be unseated and an amount of liquid lubricant corresponding to the amount discharged from the 90 upper end of tubular member 20 on the previous inward movement of the parts will be drawn from the sump into the chamber between the valves 24 and 28.

Thus it will be seen that I have provided 95 relatively simple and efficient means for utilizing the longitudinal movement of an axle for effecting a constant lubrication of the journal of the axle while the latter is in operation and said lubricating means being 100 of such structure as will enable it to be easily and cheaply produced, and requiring no attention while in service other than the maintenance of an adequate amount of liquid lubricant within the cellar.

It will be readily understood that minor 105 changes in the size, form and construction of the various parts of my improved device can be made and substituted for those herein shown and described, without departing 110 from the spirit of my invention, the scope of which is set forth in the appended claims.

I claim as my invention:

1. In a journal lubricator, a one-piece casting comprising a lubricant reservoir and 115 a pump cylinder and intake and discharge tubes leading to said cylinder from said reservoir and from said cylinder to a point adapted to be near a journal to be lubricated when the lubricator is assembled with 120 a railway journal box.

2. In a journal lubricator, a lubricant reservoir, a horizontal pump cylinder having an intake from said reservoir and having 125 an opening in its wall, a reciprocal piston in said cylinder, a strap extending from said piston through said opening, and an operating plunger secured to said strap and extending through the lubricator wall.

3. In a journal lubricator, a vertical wall, 130

an operating plunger slidable therethrough and operated from the exterior of the lubricator, a pump cylinder within said lubricator extending parallel with said plunger 5 and provided with an opening in its wall opposite said plunger, a piston in said cylinder extending lengthwise of the latter be-

yond the ends of said opening, and means rigidly connecting said piston and said plunger.

In testimony whereof I hereunto affix my signature this 5th day of April, 1921.

JAS. J. HENNESSY.
